(57) **CLAIM**

The ornamental design for swim mask configured as a sea creature, as shown and described.

DESCRIPTION

FIG. 1 is a top right side perspective view of a swim mask configured as a sea creature showing my new design. The broken line showing is for illustrative purposes only and forms no part of the claimed design; and,

FIG. 2 is a front view of the swim mask of FIG. 1.

The surfaces or portions of the article not shown in the drawing or described in the specification forms no part of the claimed design.
